WEFT DETECTOR FOR LOOMS.

Application filed December 10, 1926. Serial No. 153,963.

This invention relates to weft detectors for weft replenishing looms and it is the general object of the invention to provide a very simple weft detector formed of a very light moving part which shall have a sliding movement along a denuded bobbin to give indication of weft exhaustion.

Weft detectors of side slipping type have gone into extensive use for the weaving of certain grades of cloth and as usually made have a roughened or notched rearward extending end to engage the surface to be detected. When the weft is substantially exhausted the detector strikes the bare bobbin and moves laterally along and in contact with the bobbin, this motion being possible because the pivotal joint about which the detector moves is offset from the surface which engages the yarn. Such detectors have positive engagement with a link connected to the loom controller and because of this fact the detector must derive enough energy from the advancing lay not only to be moved itself but also to move the controller and linkage therefor.

It is an important object of the present invention to provide a side slipping detector which shall cooperate with a normally operative loom controller so related to the detector that when the latter slides along an empty bobbin the controller will remain in operative position, thus relieving the detector of the strain incident to moving the controller and linkage therefor as in the aforesaid types of side slipping weft detectors.

Detectors of the type specified have heretofore employed a spring or other resilient device to return the detector to normal position after a detecting movement and it has been found necessary to employ a spring strong enough to move the aforesaid linkage to the controller. It is a further object of the present invention to use a light spring to return the detector to normal position without sacrificing precision of action in conjunction with a support having an inclined surface down which the detector may slide after indicating, the sliding of the detector being aided by the jarring of the loom. The incline is slight and the energy necessary to lift the light wire detector up the incline is negligible, thus making it pos-

sible to use a light spring for returning the detector to normal rearward position after each non-indicating detecting beat of the loom.

As previously stated the controller is normally in operative position so that the side slipping movement of the detector shown herein is not employed to move linkage attached to the controller and for this reason it is not necessary for the detector to have a very large lateral movement. It is sufficient for the purposes of the invention to have the controller remain inactive while the detector moves so as to avoid being moved forwardly as a whole on indicating beats. It is found that as the detector rises on the aforesaid incline the roughened surface thereof not only slides longitudinally along the bobbin but also moves upwardly along the arc of the barrel of the bobbin so that the detector can travel in two directions in order to avoid the necessity of communicating the forward movement of the lay to the loom controller.

It is a more particular object of the invention to provide a detector readily adaptable to the usual form of multi-color stationary magazine weft replenishing loom of the type set forth in Patents No. 972,722 and No. 1,030,748, both to Ryon. These patents set forth an actuating floating lever which is given an operative movement on detecting beats of the loom, the action of the floating lever depending upon the position of the controller pin. Said pin is withdrawn from the path of the lever when weft is present and the said lever has an idle movement, but when weft is substantially exhausted the pin will remain under the floating lever and interrupt the movement thereof so as to initiate replenishment.

It is a more specific object of the present invention to provide a detector comprising a single element, preferably of wire, pivotally attached to the controller pin and supported in part thereby and in part by a stand provided with the aforesaid inclined surfaces. The spring customarily employed to hold the controller pin yieldingly in normal position serves also to restore the detector to normal position after each non-indicating detecting beat of the loom.

With these and other objects which will

appear as the description proceeds, the invention relates to the arrangements and combinations of parts hereinafter set forth, and more particularly pointed out in the claims.

In the accompanying drawings, wherein a convenient embodiment of the invention is shown,

Fig. 1 is a top plan view showing parts in section, the detector being in normal position,

Fig. 2 is a side elevation of the detector looking in the direction of arrow 2, Fig. 1 with the rear end of the detector omitted,

Fig. 3 is a front elevation of the detector taken in the direction of arrow 3, Fig. 1,

Fig. 4 is an enlarged section on line 4—4 of Fig. 1 through the shuttle and bobbin and showing the detector in contact with a sufficient supply of weft,

Fig. 5 is a view similar to Fig. 4 but with the detector engaging a substantially exhausted bobbin,

Fig. 6 is a detail vertical section on line 6—6 of Fig. 1, and

Fig. 7 is an enlarged horizontal section on line 7—7 of Fig. 2.

Referring more particularly to Figs. 1, 2 and 3 it will be seen that the loom frame 10 has mounted thereon the foot 11 of a weft replenishing mechanism preferably, though not necessarily, of the type shown in the aforesaid Patent No. 1,030,748 to Ryon, said mechanism having a transerrer arm indicated at 12 mounted on a stud 13 secured to the frame 11. The transerrer arm may have a pair of depending legs 14 by means of which the customary lay engaging latch, not shown, may be supported.

A stand 20 is secured to the loom frame 40 and has an upwardly projecting horn 21 slotted as at 22 to receive the right hand end of a floating actuator lever 23 pivoted as at 24 to a block 25. Said block reciprocates vertically in an arm 26 of the frame 20 by means of a rod 27 extending downwardly to a cam lever and cam not shown but located at the bottom of the loom as shown in said Patent No. 1,030,748. The left hand end of said lever has pivoted thereto an upwardly extending rod 28 connected to the replenishing mechanism not shown but illustrated in the last named patent, downward movement of said rod initiating replenishment.

Said horn 21 has a horizontal bore 29 extending across the slot 22 to receive a sliding controller pin 30. The forward end of said pin is pivotally connected as at 31 to the upper end of an arm 32 clamped to a stub shaft 33 rotatably mounted in a pair of spaced arms 34 on the stand 20. A collar 35 is secured to the shaft by means of a set screw and receives one end of a torsion spring 36 the other end of which is received by one of the bearings 34, said spring 36 acting normally to move the controller pin 30 toward

the floating actuator lever 23. As shown in Fig. 1 the right hand end of the shaft 33 has secured thereto a short arm 37 which extends rearwardly into engagement with a fixed part of the structure so as to limit 70 backward movement of said controller pin. By adjusting the arm 37 the position of controller pin 30 may be varied as desired and by varying the setting of collar 35 the pressure exerted by spring 36 to hold the controller pin in normal position may be increased or reduced. The matter thus far described is of common construction and for a further description of the same reference may be had to said patents.

The present invention relates more particularly to that portion of the device which engages the yarn or surface to be detected. A light support 50 formed of sheet metal has a table or platform 51 which is shown more particularly in Figs. 3 and 6, as slightly inclined downwardly and toward the controller pin 30. There are struck from said platform a pair of guides 52 and 53, respectively, the former being longer than and lying to the rear of the latter. The guides are spaced above and are parallel to the top of the platform as shown in Fig. 6. Said support has a depending foot 54 pivoted to a stud 55 rigid with the frame 20. A tension spring 56 interposed between the under side of support as at 57 and a pin 58 secured to the stand 20 holds said support yieldingly downwardly against an adjusting screw 59, said screw affording means for varying the vertical position of the rear end of the support.

The yarn engaging element comprises a single piece of wire 70 the rear end of which is bent as shown in Fig. 1, and provided with notches or teeth 71 of such proportion as to embed in the yarn when a sufficient supply of weft is present. Said detector has a substantially straight forwardly extending portion 72 which passes under the guides 52 and 53 and over the inclined platform 51. Said wire is further bent to the left as at 73 to lie in front of the legs 14 of the transerrer arm and then extends to the left and has formed therein an eye 74 which is loosely fitted over the controller pin 30. A collar 75 is secured to the pin 30 and serves to limit rearward movement of the eye 74, the latter being loosely confined between the collar 75 and the upper end of arm 32. As shown in Fig. 3 the eye 74 is somewhat higher than the straight-forwardly extending portion 72 of the detector wire although this relation is not considered vital.

In operation, the spring 36 serves to hold the controller pin 30 normally under the actuator lever 23 and also serves to hold the detector in rear position by means of the connection between said detector and the controller pin. Because of the inclination of

platform 51 the straight portion of the detector will move against the left end of at least one of the guides 52 or 53, constant jarring of the loom while the latter is in operation vibrating the detector sufficiently to insure the placing of the detector in the position shown in Fig. 1. As the lay advances with a sufficient supply of weft the latter will be penetrated by the teeth 71 and the detector, as well as the controller pin 30, will be moved forward. As the lay reaches its extreme forward position the actuator lever 23 will have a downward idle movement, leaving rod 28 unmoved. When insufficient weft for continued weaving is present, however, the advancing bobbin will not have holding engagement with the teeth of the detector and the latter will therefore be free to slide along the bobbin. Because of the fact that the teeth are offset from the eye 74 said detector will move to the position shown in dotted lines in Fig. 1. As the lay advances the detector will not only move angularly but will be moved up the inclined surface of the platform 51 and therefore will move over the curved surface of the bobbin B. The detector is therefore able to accommodate the movement of the advancing lay in two ways, i. e. by sliding along the bobbin longitudinally and by climbing up the curved surface of the bare bobbin. As the lay reaches the forward position therefor the controller pin will have been unmoved and the actuator lever 23 will be interrupted in its downward movement as to depress rod 28, thereby initiating replenishment.

As the lay recedes after a non-indicating detecting beat the spring 36 will serve to return both the controller pin and the detector to the normal position shown in Fig. 1, and after the detector is moved laterally at the time of indication the same will return to its normal position because of the jarring of the loom and the inclination of the platform 51. The shuttle S has a slot 80 through which the detector passes, the slot extending, if desired, upwardly in the front wall of the shuttle to permit the upward movement of the detector.

Although the invention is set forth in connection with a multi-color weft replenishing mechanism of the type shown in the later patent to Ryon previously referred to, yet the invention is not necessarily limited to this form of mechanism. The detector is equally effective either to initiate replenishment or to stop the loom.

From the foregoing it will be seen that the weft detector set forth herein is exceedingly simple, comprising essentially a single element loosely connected to the controller pin and deriving part of its support from said pin. It will also be seen that the platform, by reason of its inclination, tends to return the detector to normal position after

an indicating movement, said return movement being facilitated by the jarring of the loom.

Having thus described our invention, it will be apparent that changes and modifications may be made therein by those skilled in the art without departing from the spirit and scope of the invention, and we do not wish to be limited to the details herein disclosed but what we claim is:

1. In a weft detector for looms, a side slipping weft detecting element, a support for said element having a vertically inclined surface at the lower portion of which said detector is normally disposed, and yielding means to hold said detector in bobbin engaging position, said detector at the time of exhaustion of weft sliding along the bobbin and up the inclined surface to give indication of weft exhaustion, said yielding means remaining at rest when the detector rises up the inclined surface, said detector moving down the incline surface to assume normal position after an indicating movement.

2. In a weft detector for looms operating with bobbins having cylindrical body portions, a side slipping weft detecting element to engage the bobbin on each detecting beat of the loom, a support for said element having a vertically inclined surface at the lower end of which the detector is normally located, yielding means to hold said detector in bobbin engaging position, and a normally operative loom controller moved out of controlling position when said element engages a sufficient supply of weft, said detecting element moving along a denuded bobbin and also up said inclined surface and vertically along the cylindrical surface of the bobbin, said controller remaining in normal position to indicate weft exhaustion, and said yielding means remaining at rest when the detector rises up the inclined surface.

3. In a weft detector for looms operating with normally horizontal bobbins having cylindrical detector engaging portions, a detecting element movable along the surface to be detected at the time of substantial exhaustion of weft, a vertically inclined support at the lower end of which said detector element is normally disposed, a forwardly yieldable member operatively connected to the detector to be moved forwardly by the detector to prevent indication of weft exhaustion and remaining at rest when the detector moves up the inclined and along and over a denuded bobbin, said element moving up said inclined surface to give indication of weft exhaustion without moving the yielding member and being movable down said inclined surface to normal position after indication, said movement being facilitated by the jar of the loom as the latter runs.

4. In a weft detector for looms, a weft detecting element, a support therefor having an inclined surface at the lower end of which said detector is normally disposed, a loom controller, means defining an operative loose connection between the element and controller, a single resilient device operatively related to the controller and holding said controller yieldingly in operative position and also holding said detector yieldingly in detecting position, said resilient device yielding on detecting beats of the loom when sufficient weft is present and said detecting element moving said controller to inoperative position, and said detecting element moving laterally along the bobbin and up the inclined surface when insufficient weft is present, said yielding device and controller remaining at rest when said detecting element moves up the inclined surface to give indication of weft exhaustion.
5. In a weft detector for looms, an actuator to effect a change in the operation of the loom, a controller for said actuator normally operatively placed with respect thereto, a detector element pivotally mounted on the controller, resilient device to hold the controller and detector yieldingly in normal rearward position, and means defining a vertically inclined surface up which the detector moves at indication of weft exhaustion while the resilient device is at rest, said detector normally lying at the lower end of the inclined surface and moving down the latter after indication to return to normal position.
6. In a weft detector for looms, an actuator to effect a change in the operation of the loom, a controller for the actuator, a detecting element connected to the controller to move forwardly therewith and formed of wire and pivotally mounted on the controller, said element having a portion extending rearwardly and spaced from the controller and having yarn engaging teeth cut therein, a support having a vertically inclined surface at the lower end of which said detector normally lies, said detector moving along a denuded bobbin and up the inclined surface to give indication of weft exhaustion while the controller remains at rest, said detector moving down the inclined surface to return to normal position after giving indication, and a single resilient device holding said controller and detector yieldingly in normal position.
7. In a weft replenishing mechanism for looms, a transferrer arm having a portion thereof movable forwardly at the time of transfer, an actuator having a regular move-
- ment on detecting beats of the loom, a controller for the actuator normally operatively related to the actuator to interrupt movement thereof on detecting beats of the loom, a detecting element supported by and pivotally mounted with respect to the controller, said detector comprising a bent wire having a portion thereof extending in front of that portion of the transerrer arm which moves forwardly on detecting beats of the loom, said wire also having a yarn engaging surface at the rear thereof offset in the direction to length of the surface to be detected with respect to the pivoted connection between said detector and the controller, said transerrer arm on transferring beats of the loom having direct engagement with the bent wire to withdraw the same from the path of the incoming supply of weft and also to move said controller out of the path of the actuator.
8. In weft detecting mechanism for looms, an actuator having periodic movement in a prescribed path, a controller for said actuator normally lying in the prescribed path, a weft detector pivotally mounted on the controller and having a rearwardly extending portion to cooperate with and detect the presence of yarn in the active shuttle, a resilient device acting jointly on the controller and detector to move said controller and detector in a horizontal plane toward the surface to be detected, and means defining a vertically inclined plane up which said detector may slide while in contact with a denuded bobbin, said detector when moving up the incline acting to leave the controller at rest in the path of the actuator to initiate replenishment.
9. In a weft detector for looms, a regularly moving actuator, a controller therefor normally in the path of the actuator, a side slipping weft detector pivotally mounted on the controller, resilient devices yieldingly holding a detector and controller in rear position and operating to exert a force on said controller and detector having a horizontal component, said devices yielding forwardly when the detector engages a sufficient supply of weft to withdraw the controller from the path of the actuator, and an upwardly inclined surface along which the detector slides against the action of gravity at the time of weft exhaustion without moving the controller pin against the action of the yielding devices.
- In testimony whereof we have hereunto affixed our signatures.
